Attorneys

UNITED STATES PATENT OFFICE.

HARRY LEWIS RUSSELL, OF KEENE, NEW HAMPSHIRE, ASSIGNOR TO C. L. RUSSELL AND SONS, A PARTNERSHIP COMPRISING HARRY L. RUSSELL, OF KEENE, NEW HAMPSHIRE, AND GEORGE T. RUSSELL, OF WEST SWANZEY, NEW HAMPSHIRE.

CHAIR ASSEMBLY.

Application filed October 7, 1925. Serial No. 61,003.

To all whom it may concern:

Be it known that I, HARRY LEWIS RUSSELL, a citizen of the United States, residing at Keene, in the county of Cheshire, State of 5 New Hampshire, have invented certain new and useful Improvements in Chair Assemblies, of which the following is a description, reference being had to the accompanying drawing, and to the figures of reference 10 marked thereon.

This invention relates to improvements in chair assemblies, and more particularly to methods and apparatus of semi-assembling chairs at the factory in such manner that 15 the parts of the chair which must be held in fixed relation during shipment are connected, and the remaining parts are adapted to quick attachment at the point of distribution.

According to this invention, the seat is mounted pivotally upon the front standard, and in packed condition lies parallel thereto; but may be readily swung into the final or 25 assembled position at right angles thereto, and held in such position by the assembly of the remaining portions of the chair. In this way, the final assembly is facilitated and cheapened; and the space occupied by the several parts during shipment is reduced to 30 a minimum.

In the drawings:

Fig. 1 is a side view of the seat and front standard, with the remaining portions of the chair indicated in dash lines, and the seat 35 in a folding position in dotted lines.

Fig. 2 is a horizontal section on line 2—2 of Fig. 1.

Fig. 3 is a perspective view of a front bracket.

The chair has the front standard including the posts 10 and the rungs 11 which are rigidly assembled with regard to each other at the factory by nailing and gluing. The rear standard includes the corresponding 45 posts 12 and rungs 13, and may likewise be rigidly assembled at the factory. The seat includes the side spars 14, the front spar 15 and the rear spar 16.

The front spar 15 is provided with the tenons 15^a to engage in the front posts 10, and constitutes in effect a rung for the front standard and is rigidly assembled therewith at the factory.

The side spars 14 are mounted by means of

the front brackets 17 so that they are capable of rotating about the axis of the front spar 15, but are held in a plane offset from this axis by the shape of the brackets, so that the side spars in the finished condition of the chair are somewhat above the front 60 spar. The side spars 14 have tenons 14^a at both ends to be received in the four posts, to support and brace the assembled chair. The rear spar 16 is rigidly mounted with regard to the side spars 14 by rear brackets 18 65 similar to the front brackets 17, but it will be noted that the rear spar itself has no long projecting tenons to engage the rear posts.

The cane bottom indicated generally at 19 may be placed upon the assembly of the 70 front, side and rear spars, and then the front standard built upon the front spar. The several parts as semi-assembled may then be crated and shipped to a point of distribution. The distributor then uncrates the 75 chair parts, swings the side and rear spars of the seat upward into the full line position of Fig. 1, in which manner the tenons 14^a of the side spars are passed into the holes 10^a in the front posts 10, by reason of the offset relation of the plane of these tenons 80 with regard to the front spar 15. Glue may be applied in the holes 10^a to assist in holding the parts in this position. The rear 85 standard may then be applied as indicated by the arrow in Fig. 1 to clamp the side rungs 22 in place; and finally the arms 20 and the rockers 21. Glue and nails may be employed to hold the several tenons and 90 mortices together. The several parts of the chair are thus braced and connected together.

The brackets as shown in Fig. 3 are formed from sheet metal by cutting and punching to shape. They each have the lower eyes 25 to engage the tenon on a front or rear spar, an intermediate section 26 formed integrally therewith and extending upwardly, outwardly and rearwardly in the case of the front brackets, and upwardly, outwardly 100 and forwardly in the case of the rear brackets, to clear the respective posts; and the integral upper eyes 27 which receive the respective side spars 14; so that the spars are severally held with their axes substantially in planes passing through the axes of the respective posts. It is preferred to form 105 the nail holes 28 in the eyes to assist in

holding the spars together: the shoulders of the tenons assure an invariable position of the brackets in the finished chair.

It is obvious that the invention is not limited solely to the specific construction and assembly shown, but any modifications may be made therein within the scope of the appended claims.

Having thus described my invention, what I claim is:

1. In a chair construction, an assembled front standard of posts and transverse rungs, a seat, brackets pivotally supporting said seat from one of said rungs in a plane offset from the axis of the rung, a rear standard adapted to be attached to said seat, and bracing means adapted to hold said standards and seat in fixed interrelation.

2. In a chair construction, an assembled front standard of posts and transverse rungs, side spars and a rear spar for a seat, a seat bottom attached to said spars and one of said rungs, brackets pivotally supporting said side spars on said rung which is attached to said bottom, brackets rigidly sup-

porting said rear spar from said side spars, a rear standard adapted to be attached to said side spars, and bracing means adapted to hold said standards and spars in fixed interrelation.

3. In a chair construction, an assembled front standard of posts and transverse rungs, side spars and a rear spar for a seat, a seat bottom attached to said side and rear spars and one of said rungs, brackets having eyes at the upper ends to receive said side spars and at the lower ends to receive the said rung which is attached to said bottom and adapted to support said side spars in a plane offset from the axis of said rung and in the plane of the axis of the respective front posts, a rear standard, means on said side spars to engage said rear standard, and bracing means to hold said standards, brackets and spars in fixed interrelation.

In testimony whereof, I affix my signature.

HARRY LEWIS RUSSELL.
